MULTIPLE UNIT FILE

Louis W. Karlen, Buffalo, N. Y., assignor to Remington Rand Inc., Buffalo, N. Y.

Application November 23, 1935, Serial No. 51,330

4 Claims. (Cl. 129—25)

This invention relates to paper files and binders. The invention provides a paper file for independently mounting groups of papers in attached relation in a file in such a manner that independent access to the papers in any group may be had for reference, or the attachment or removal thereof.

The invention comprehends the provision of a suitable folder or backing sheet for supporting the file having a bendable prong paper fastener, and a series of filler sheets. Each filler sheet has a bendable prong fastener on a sheet supporting section thereof and an attaching section formed for engagement on the fastener of another filler sheet, or the fastener on a folder or backing sheet. Each of the filler sheets may be attached one to the other in successive order and the end sheet attached to the folder or backing sheet by means of the attaching portion. The attaching portions are in each case located at the same side of the sheet supporting section as the fastener, so that independent groups of sheets may be engaged on the bendable prongs of each fastener on top of the attaching portion of a superimposed filler sheet, thereby providing for independent attachment and removal of sheets from any fastener in the usual manner without interfering with the attachment of one filler sheet to another or to the folder or backing member. Reference may be had to any sheet of any group through moving the sheet supporting section of the overlying filler sheet away from the group of sheets to which reference is to be made. This provides for the application and removal of sheets, or reference thereto, in any group through the usual manner of using the bendable prongs on the fastener mounting the desired papers, the filler sheets moving the overlying groups of sheets away from the one desired to entirely uncover the desired group.

In the drawings:

Fig. 1 shows a file constructed according to the invention in perspective, using a folder for supporting and containing the file papers and a group of filler sheets attached to one another and to the file in successive relation, the folder being shown open and one of the filler sheets and the group of sheets mounted thereon being turned upwardly and away from the adjacent group of sheets in the file to provide access thereto.

Fig. 2 is a fragmentary cross section taken on line 2—2 of Fig. 1.

Fig. 3 is a cross section taken on line 3—3 of Fig. 2.

Fig. 4 shows two filler sheets in perspective, one

of which is shown elevated above the other and arranged at an angle thereto for illustrating the details of construction of the filler sheets, one of the filler sheets having a portion broken away to show the method of mounting the paper fastener. 5

Fig. 5 shows another form of filler sheet construction in perspective.

A suitable backing or supporting structure for the file is provided by the invention and as illustrated in the drawings is shown in the form of 10 a folder 1 having covers 2 and 3 provided with a flexible connection 4 providing a hinged connection in forming the folder so papers may be enclosed between the covers.

The cover 2 is formed with an index tab 5, 15 when desired, for receiving the usual indexing information used for indexing the file in a manner well known in the art.

A bendable prong fastener 6, preferably of the type having a base 7 with a pair of separated 20 prongs 8, is mounted on the cover 2 at the upper end as illustrated in Fig. 1. The base portion 7 of the fastener is engaged against the back of cover 2 having an offset portion 9 formed in the cover to receive the fastener base 7. Bendable 25 prongs 8 extend through slots in cover 2 and project through the front side or inside of cover 2 in order to receive and mount a group of papers indicated generally at 10 in Figs. 2 and 3 and secure the same to cover 2. Bendable prongs 8 30 project through the papers forming the group 10 in the usual and well known manner and have the ends bent downwardly against the upper face of the paper preferably by extending the ends outwardly away from each other in the manner illustrated in the drawings.

Other groups of papers may be secured in the folder in independent relation by means of this invention. For this purpose a filler sheet 11 is provided for each additional group of papers. 40 Each filler sheet comprises a sheet supporting section 12 having an extension from one end forming an attaching portion or flexible or foldable section designated 13, terminating in a marginal portion or section 14 formed with openings 45 15 at properly spaced intervals for receiving bendable prongs 8. Marginal portion 14 forms an attaching margin for attaching the filler sheet to another filler sheet or to the folder.

Each filler sheet is provided with a fastener 16 50 having a base portion 17 engaged against the back face of sheet supporting section 12. A pair of bendable prongs 18 extend through openings in the sheet supporting section and project from the opposite or upper face of the filler sheet. 55

Fasteners 16 are duplicates of fasteners 6 for securing uniformity in the file and provide for interchangeability of filler sheets. The fasteners 16 are mounted in the backing sheets in the same manner that fastener 6 is mounted in cover 2. Since fastener 6 is located at the upper end of cover 2, a fastener 16 has been located at the upper end of sheet supporting section 12 on each filler sheet and adjacent to the end of the sheet from which the attaching portion or flexible intermediate section 13 of the filler sheet extends. This provides a uniform relation between the several fasteners so that in the assembled file they will be mounted in the corresponding position 15 in the file and superimposed in the closed position of the file as shown in Fig. 3.

One of the filler sheets 11 has the attaching portion 14 engaged over prongs 8 of fastener 6 in the manner illustrated in Figs. 2 and 3, the 20 prongs 8 extending through the apertures or slots 15. Where it is desired to support more than one group of sheets in the folder, these 25 filler sheets are used and the attaching portion of the filler sheet has its marginal portion 14 engaged over the fastener prongs 8 in the folder before papers are filed on prongs 8. In this way 30 marginal portion 14 of a filler sheet 11 will be located adjacent to the inner face of cover 2. The body of sheets 10 applied to fastener prongs 8 will then lie on top of marginal portion 14 of the first filler sheet.

The first filler sheet may be moved upwardly and away from the top face of the papers on fastener prongs 8, the bendable or flexible intermediate section 13 providing for this operation 35 in the file so that full access to apply, remove or refer to papers on prongs 8 may be had in a highly convenient manner.

The drawings show the application of several 40 filler sheets in the file in order to illustrate that where more than one filler sheet is used in the file, the second filler sheet will have the marginal portion 14 thereof applied by inserting the prongs 18 on the fastener 16 carried by the first filler 45 sheet through apertures 15 of the second filler sheet. Then a group of papers may be independently applied to prongs 18 on the fastener of the first filler sheet, a group of such papers being indicated at 19. A third filler sheet may be applied 50 to the fastener on the second filler sheet in the same manner and a body of papers 20 may then be applied to the fastener prongs 18 of the fastener on the second filler sheet. Where 55 no additional filler sheets are to be used, another group of papers 21 may be applied to the fastener on the third filler sheet.

Figure 1 illustrates the use of three filler sheets with the groups of papers independently mounted on the fasteners of each sheet and the folder as 60 above described. Figure 1 also illustrates the third filler sheet moved away from the group of papers carried by the fastener on the second filler sheet to illustrate how access may be had to the group of papers carried by any filler sheet 65 or by the fastener on the folder for reference to such papers or for the manipulation of the prongs for applying or removing papers from any fastener without disturbing any of the papers carried by the other fasteners and forming the other 70 independent groups of papers.

Index tabs 22 may be provided on the edges of the filler sheets and where it is desired to use a series of filler sheets in a single file, these filler sheets may be made so that the tabs on each 75 successive sheet are offset laterally one from the

other in order to provide full visibility of each of the tabs. As illustrated by the drawings the filler sheets are preferably constructed of a larger size than the sheets of paper that will be filed on the fasteners carried thereby in order to 5 provide a marginal portion on each filler sheet projecting beyond the margin of the filed papers. In this way the tabs 22 will project outwardly 10 away from the filed papers in the folder and supplement the index on tab 5 of the folder so that ready reference may be made to a desired 15 group of papers by selecting the proper tab.

With the folder and filler sheets constructed as above described and as illustrated in the drawings, it will be noted that when the papers are 15 in filed relation all of the filler sheets will be superimposed one on the other so that the different groups of correspondence or papers in the file will be superimposed one upon the other. In this position the fasteners will be in superimposed 20 aligned relation and the base portion of one fastener will lie between the outwardly extending prongs of the fastener below as shown in Fig. 3, and in this way extra thicknesses of material in superimposed relation creating a build-up in the 25 file will be reduced to a minimum.

It will be understood that the fasteners may be placed in the folder in any position, for example, instead of the fastener being mounted in the back cover 2 at the upper end, it may be 30 placed along the side adjacent hinge strip 4 connecting the covers, or in any other desired position. The fasteners in the filler sheets may also be arranged in any position on the filler sheets and the attaching portion may be formed on any 35 margin of the sheet supporting section of the filler sheet.

For example, a filler sheet may be constructed as shown in Fig. 5 indicated by numeral 23. The 40 filler sheet 23 is provided with sheet supporting section 24 having an index tab on one margin at 25 and an attaching portion comprising a flexible section 26 and attaching margin 27 formed along and extending from a side edge of sheet supporting section 24. A bendable prong 45 paper fastener 28 is mounted along the side margin of the sheet instead of at the end, as illustrated. This type of filler sheet would be used in a folder or with a backing member that would 50 preferably have the paper fastener mounted in a corresponding position along the side to that shown in Fig. 5.

In order to provide the intermediate section 13 so that it will be readily flexible and will hinge in a substantially uniform manner, section 13 is 55 scored along lines 29 and 30 where section 13 joins with sheet supporting section 12 and marginal portion 14 respectively. The intermediate portions of flexible section 13 may also be scored so that it will readily bend and adjust its shape 60 to conform with the file in which the filler sheet is placed and expand with an increase in the thickness of the group of papers that will lie between marginal portion 14 and sheet supporting section 12.

The invention claimed is:

1. A multiple unit file comprising a backing member, a bendable prong fastener mounted on said backing member for detachably receiving and securing a unit of sheets to said backing 70 member, a filler sheet having a sheet supporting portion, a mounting margin and a flexible section connecting said margin to said sheet supporting portion, and a bendable prong fastener mounted on said sheet supporting portion, said mounting 75

margin having the prongs of said first-mentioned fastener engaged therethrough for attaching said margin to said backing member between a unit of sheets thereon and said backing member, and said sheet supporting portion being movable on said flexible section into and out of superimposed relation on the sheet unit carried by the first-mentioned fastener, said second-mentioned fastener being adapted to detachably support another sheet unit independent of the first whereby the sheets in each unit may be independently removed and replaced on the fastener thereof without disturbing the assembly of the filler sheet and backing member.

5 2. A multiple unit file comprising a backing member, a bendable prong fastener mounted thereon, a plurality of filler sheets, each having a margin formed with apertures to receive fastener prongs, a foldable section on said margin and a sheet supporting section attached to said foldable section, and a bendable prong fastener on each sheet supporting section, all of said fasteners being uniform and adapted to detachably mount a series of sheets for support thereon independent of the sheets on the other fasteners, the margin of each filler sheet having the openings therein receiving the prongs of a fastener not carried thereby and being detachably mounted on the fastener beneath said series of sheets thereon to interconnect all said filler sheets one to another in series and the end one of said series to said backing member for supporting said sheets in superimposed relation with said foldable sections arranged in folded relation, each of said 10 filler sheets being movable to provide access to any of said series of sheets on said fasteners independent of the others for inspection, placement and removal.

15 3. A multiple unit file comprising a plurality of supporting sheets each formed of a single piece of material and each adapted to form a backing for independent groups of sheets, a bendable prong fastener on each backing for removably receiving and attaching a group of sheets thereto, and attaching portions on the supporting sheets forming each backing for detachable engagement with the fastener on an adjacent backing between the backing and group of sheets thereon for connecting said backings together successively in chain-like form with said backings supporting said groups of sheets, in superimposed relation in one position, and each backing being movable on its attaching portion whereby said sheets may be moved out of superimposed relation for providing independent access to the fastener and the group of sheets thereon for removal or reference.

20 4. A multiple unit file comprising a plurality of filler sheets each having a sheet supporting section carrying a bendable prong fastener and a flexible attaching portion formed with fastener prong receiving openings in the marginal portion, and a folder formed to provide a pair of hingeable covers, a bendable prong fastener on one of said covers, a flexible attaching portion on one of said filler sheets having the prongs of the fastener on said folder engaged through the openings therein, and the flexible attaching portion of each remaining filler sheet having the openings therein successively engaged with the fastener prongs on the filler sheet attached to said folder and each succeeding filler sheet for hingedly connecting said filler sheets together successively and to said folder in chain-like manner, each of the fasteners carried by said folder and filler sheets being adapted to independently receive groups of papers on top of said attaching portions, and the covers on said folder being adapted to enclose all of said sheets therein.
